PRESS-DOOR COUNTER-BALANCE

Frank S. Perry, Gorman, Tex.

Application October 12, 1931. Serial No. 568,491

3 Claims. (Cl. 100—19)

This invention relates to new and useful improvements in press-door counter-balances.

One object of the invention is to provide an improved counter-balance for the door of a press box of the type in which the door is hinged at its bottom and swings outwardly and downwardly, such as are used on cotton presses and the like.

A particular object of the invention is to provide a counter-balance which will be entirely out of the way of the workmen when the door is closed and which may be mounted above the press box so as to utilize a space ordinarily not used.

Another object of the invention is to provide a counter-balance in which the balancing will be the same at substantially all positions of the door, thus eliminating strong points and weak points in the swinging arc of the door and making for easier and safer handling of the door.

A further object of the invention is to provide a counter-balance which may be entirely detached from the press-box door when the door is closed and while the box is being swung from one position to the other.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a side elevation of a portion of a press-box and its frame equipped with a counter-balance constructed in accordance with the invention.

Figure 2 is an end elevation of the same, the doors and counter-balance being shown in the closed position in full lines and in a partially open position in dotted lines.

Figure 3 is a sectional detail of one of the balances.

Figure 4 is a horizontal cross-sectional view of one of the weights, and

Figure 5 is a perspective view of one of the clevises.

In the drawings the numeral 10 designates an end standard and 11 a similar standard. Each standard has a transverse channel bar 12 at its bottom and a gusset plate 13 at its top. The standards are mounted transversely across the top beams A of the press frame. The bars 12 are suitably fastened to the beams, the standard 10 being at one end of the beams and the standard 11 spaced inwardly therefrom on said

beams. The standards are further secured by angular braces 14. The standards constitute supports and may be of any suitable construction and fastened on the beams in any suitable manner.

A transverse fulcrum bar or shaft 15 is fastened in the plates 13 and connects the tops of the standards. A pair of counter-balances are mounted on the shaft and each includes an elongated bar or lever 16 which is journaled near its center on the shaft, a weight 17 slidably mounted on the lever, and hangers 18 also journaled on said shaft and suspending said weight.

Each lever has an integral bearing box 19, whereby an amplified bearing surface on the shaft 15 is provided. The box is rotatably confined between collars 20 fastened on said shaft. Each hanger has an eye 21 hinged on the shaft and its lower portion is screw-threaded and telescopes a recess 22 in the side of the weight 17, as is shown in Figures 3 and 4. Angular stirrups 23 embedded in the upper end of each weight are adjustably supported on the hangers by nuts 24. By adjusting the nuts the weights are raised or lowered, thus varying their distance from the shaft or fulcrum 15.

On the upper end of each lever is fastened a clevis 25 and each clevis has an eye 26 extending from one edge of the lever. One clevis is directed oppositely from the other, whereby the eye of each overhangs one of the doors B on the opposite sides of the press-box C. A flexible connection such as a cable, chain or rope 27 is provided for each lever. I have illustrated ropes in the drawings, and each rope has its upper end looped and fastened to the eye 26 of one of the clevises. Each rope has a hook 28 at its lower end.

While each hook 28 may be engaged with its respective door in any suitable manner, I prefer to mount in each cleat D, an eye bolt 29, and engage the hooks in these eyes. It will be seen that one of the eye bolts will be spaced inwardly from the end of the door so that the ropes may hang in the vertical planes of the levers 16.

By making the distance from the fulcrum shaft 15 to each eye 26, substantially equal to the distance from the hinge E of each door to the eye of its bolt 29, the arcs in which the eyes 26 and 29 swing will each have the same radius. Then by adjusting the nuts 24 so that the weights 17 are spaced a sufficient distance from the fulcrum shaft 15 to counter-balance the weight of the doors, said doors may be easily swung and safely opened and closed. This arrangement will give

an even counter-balancing of the doors at all positions of their swing.

When the doors are fully open and slightly below the horizontal the initial lift by the workmen will not require any more energy than that necessary to swing the doors at any other position, when closing the same; also the latter part of the downward swing will not require any more resistance by the workmen than any other position of the said swing. When the doors are closed the hooks 28 may be disengaged from the eye bolts 29 and the press-box freely swung. The entire device is out of the way and all parts except the ropes are mounted above the press-box.

15 Various changes in the size and shape of the different parts, as well as modifications and alterations, may be made within the scope of the appended claims.

Having illustrated and described a preferred form of the invention, what I claim, is:

20 1. In a counter-balance for a press-box door, an upright support, a shaft carried by the support, an elongated lever pivoted intermediate its ends on said shaft, hangers pivoted on the shaft, 25 a weight slidably confined on the lever, stirrups on the weight engaging the hangers, a clevis at the upper end of the lever, and a flexible connection suspended from the clevis and having a hook at its lower end.

30

2. A counter-balance for press box doors comprising, a pair of upright standards, a shaft extending between and carried by the upper ends of said standards, an elongated lever journaled on the shaft at its mid-portion, the lower end of the lever terminating short of the bottoms of the standards, a weight mounted on the lower end of the lever, and a flexible connection having one end secured to the upper end of said lever and provided at its opposite end with means for attaching it to a press-box door.

80 3. The combination with a press-box having upright doors on opposite sides thereof mounted to swing downwardly, a pair of upright standards mounted on top of the box relatively between the doors, a shaft extending between and carried by the upper ends of the standards, said shaft being disposed longitudinally of said doors, a pair of elongated levers journaled at their mid-positions on the shaft, the lower end of each lever terminating short of the bottoms of the standards and above the top of the press-box, each lever having a weight at its lower end and a flexible connection extending from its upper end, one of said flexible connections being attached to the upper portion of the door on one side of the box and the other flexible connection being attached to the upper portion of the door on the other side of the box.
